[Redacted]
Matthews & Kahles,
Rice & Clover Hulling Machine,
Patented Jan. 17, 1834.

90. The Schedule referred to in these letters Patents and making part
of the same containing a description in the words of the said Barnes, H.
Matthews & Matthew S. Hahle, themselves of their improvement being
a Clover and Rice Hulling Machine.

See it known that we, Barnes, H. Matthews and Matthew S. Hahle
of the Town of Lexington, County of Rockbridge, and State of Virginia, have
made an improvement in the useful art, being a machine for separating
the seeds of Clover and Rice from their stalks, and clearing the straw by
a revolving fan, entitled "Matthews and Hahle's Clover and Rice Hulling
Machine" which is described as follows, reference being had to the annexed
drawings.

This machine consists of the following principal parts.

A frame for containing and supporting the machinery;
A cylinder for breaking the heads of clover, and performing the rough
part of the operation; another cylinder, placed below this, for more per-
fectly hulling or rubbing out the seed;

A revolving fan for clearing; and the gearing by which the whole
machinery is moved.

The Frame, a, is adapted, in size and strength to receive and
contain the machinery; it is made close at the two sides, with openings
by, in the rear to admit the chaff or rubbish to escape, and for the work
men to attend to the operation of the cylinders in hulling the seed.

At the top of the machine is placed a cylinder, c, made of wood
of any convenient diameter and length, covered with emery, coarse
wire pine, or sheet iron furnished in holes, having the projections, facing
outward; having an judges, supported on the frame, and revolving
in a hollow segment bed, d, made of wire or punched sheet iron.

Over this cylinder the frame rises and forms a kind of hopper, in
into which the heads of clover and rice to be cleared are first put;

This cylinder is for breaking the heads and separating the straw and
chaff from the seed. the seed falling through the concave, raised, bar-

to the lower roller.

Below the first mentioned cylinder is placed another cylinder, of any convenient size, made of wood, and covered with shark skin, sole leather, or any other suitable material, made waterproof of gum, shellac, or which is laid or powdered, sand, emery, glass, or any other gutty substance.

This cylinder also turns upon guides supported on the frame, and revolves in a concave bed, q, covered with shark skin leather, or other suitable material; the seed descending upon a screen, h, placed below where it is cleaned.

The use of this second or fine cylinder is to shell the seed more perfectly than is done by the first or coarse cylinder: however, one cylinder only, covered with a suitable material, may be made to answer this purpose of both; but two will in most cases be found preferable.

Below the finishing cylinder is placed a Revolving fan, i. for blowing off the chaff; it is made in the usual form, and turned by the main driving power.

The gearing by which the cylinder and wirewinding or framing machinery are driven, is placed outside of the casing of the frame, and may consist of cog wheels, &c., or pulleys fixed on the axles of the cylinders, turned by a crank by manual power; or by straps and pulleys worked by horse or other power.

The framing machine is turned by a steel passing over a pulley on the axle of the lower cylinder (when two are used) and a pulley on the axle of the revolving fan.

Operatives. The clover heads or Rice, are fed into the hopper or top, or, of the frame above the upper cylinder, and the machine, being put in motion, carries the materials between the cylinders, and bed, &c., whereas the straw and chaff are separated; this machine, giving this, the clover ~~and~~ bed; and the chaff and straw passing off this, are opening, and, under one the desire for that purpose having the seed, partly cleaned, now descends to the second, or lower cylinder, & with bed, & covered with leather (*****)

192
upon a screen, &c, where in descending the chaff is blown off by the fan,
& then the seed falling upon the screen below passes thro' it
to the floor or into a vessel placed below to receive it, when one cy-
linder only is used then the seed passes immediately from it to the
winnowing machine.

The invention here claimed consists in the peculiar construction
of the machine for hulling clover seed and rice with the combination
and arrangement of its several parts as above described.
